(57) **CLAIM**

We claim the ornamental design for a pet collar tag, as shown and described.

DESCRIPTION

The intended use of the article in which the design is embodied is pet collar identification.

FIG. 1 is an isometric view of a pet collar tag according to our new design;

FIG. 2 is a rear view thereof; and

FIG. 3 is a front view thereof.

Portions of the drawings which are rendered in broken line are for illustrative purposes only and form no part of the claimed design.

Characteristic feature of the design reside in the configuration of a pet collar tag to suggest extended wings in background and to suggest a pet related image in the foreground.
